US00D512694S

(12) **United States Design Patent** (10) Patent No.: **US D512,694 S**
Kim et al. (45) Date of Patent: **** Dec. 13, 2005**

(54) **LIGHT-EMITTING DIODE**

(75) Inventors: **Chang Wook Kim**, Kyungki-do (KR);
Seon Goo Lee, Kyungki-do (KR);
Kyung Taeg Han, Kyungki-do (KR)

(73) Assignee: **Samsung Electro-Mechanics Co., Ltd.**
(KR)

(**) Term: **14 Years**

(21) Appl. No.: **29/220,220**

(22) Filed: **Dec. 27, 2004**

(30) **Foreign Application Priority Data**

Jun. 30, 2004 (KR) 30-2004-0019638

(57) **CLAIM**

The ornamental design for a light-emitting diode, as shown and described.

DESCRIPTION

FIG. 1 is a perspective view of a light-emitting diode;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom view thereof.
